TOY BUS

Norman Spiegel, New York, N.Y., assignor to
Nasta Industries, Inc.

Filed Dec. 21, 1971, Ser. No. 210,633

Term of patent 14 years

Int. Cl. D21—01
U.S. Cl. D34—15 AJ

FIG. 1

FIG. 2

FIG. 3

FIG. 4

FIG. 1 is a top plan view of a toy bus showing my new design;

FIG. 2 is a front elevational view thereof;

FIG. 3 is a side elevational view thereof; and

FIG. 4 is a rear elevational view thereof.

I claim:

The ornamental design for a toy bus, as shown.
